UNITED STATES PATENT OFFICE.

FRANK O. HOAGLAND, OF HARTFORD, CONNECTICUT, ASSIGNOR TO PRATT & WHITNEY COMPANY, OF HARTFORD, CONNECTICUT, A CORPORATION OF NEW JERSEY.

METAL-WORKING MACHINE AND METHOD.

1,323,276.

Specification of Letters Patent.

Patented Dec. 2, 1919.

Application filed April 5, 1917. Serial No. 159,883.

To all whom it may concern:

Be it known that I, FRANK O. HOAGLAND, a citizen of the United States, residing at Hartford, in the county of Hartford and 5 State of Connecticut, have invented certain new and useful Improvements in Metal-Working Machines and Methods, of which the following is a specification.

Both the machine and the method can be 10 used in widely-different arts, although I have found the same of particular advantage in the production of a bullet such for illustration as is used in small arms. By the machine or apparatus and the method I secure 15 a product, the longitudinal axis of which passes through the center of gravity thereof and which is peripherally smooth and free of protrusions. These are highly important factors in a great many fields, but especially 20 in the ordnance art to which my invention is primarily directed. A projectile or bullet which is balanced and which has a smooth outer surface will accurately follow a pre-determined trajectory or path. As will be 25 inferred, articles of divers character can be produced by the machine and the method, although it will be clear that both are of high efficiency in the production of a bullet especially one of the type used in small arms 30 such as a rifle or pistol. Necessarily the blank initially has upon its surface one or more excrescences, and these I remove, the result being as already stated a product which is circumferentially smooth. In the 35 operation by the machine the surface roughnesses are entirely obliterated and, what is more important, the resultant article is perfectly or practically perfectly balanced longitudinally. The machine comprises mechanism 40 for supporting a blank and for applying a succession of blows to the blank upon its surface. This result I can obtain in any one of various ways. For instance while the blank is being supported it can be turned 45 about its axis, generally its longitudinal axis, and there can be applied to its outer surface a large number of percussive effects which are usually exerted throughout the length of the blank of whatever character 50 the same may be.

I have referred to the fact that in the practice of my invention a blank of suitable character is provided. The nature of the blank will depend in a measure, if not altogether, upon the ultimate article. While I

have also referred to the point that both the machine and method are capable of wide use, I will describe the same, however, as adapted for the production of a bullet. The blank for this article can be produced in 60 any desirable manner. In the case of a bullet this blank is approximately parabolic in cross section, being longitudinally tapered to produce a small end or practically a point and a slightly larger opposite end. This, 65 however, is merely one shape. I so treat the blank that the finished article will be as nearly as possible balanced so that the longitudinal axis or other desired line will pass through the center of gravity of the article, 70 which is a consideration of some importance. Another object, as already suggested, which I accomplish is the elimination of surface protrusions, the result being that the product is smooth or free of projections. As 75 a result of the first condition, the bullet will definitely follow a defined or prescribed path, this fact being naturally aided by the condition that the surface of the bullet is quite smooth.

In the drawings accompanying and forming part of the present specification I have shown in detail one of the several possible forms of mechanism embodying the mechanical features of the invention and adapted 85 for the practice of the method. I do not restrict myself to this particular showing and I may depart therefrom both as to the machine or apparatus and as to the method within the scope of the appended claims. 90

Referring to the drawings:

Figure 1 is a plan view of a pair of rollers, a supply hopper, a supporting device and certain coöperating parts, some of these parts being shown in section.

Fig. 2 is a face view of the rollers, their adjacent portions being broken away, this view also showing the supporting device and a blank held thereby between the rollers.

Figs. 3 and 4 are developed views of portions of the rollers shown in Figs. 1 and 2 respectively.

Fig. 5 is a transverse sectional view which may be considered as taken through the peripheral portion of either one of the rollers.

Fig. 6 is a vertical sectional view of an organized machine.

Fig. 7 is a detail view of the supplying device and certain coöperating parts.

Referring in detail to the drawings, the 110

numerals 2 and 3 represent two coacting rollers rotatable about parallel axes which may be horizontal, vertical or otherwise. As illustrated these rollers are fastened to the 5 inner ends of horizontally disposed shafts as 4 and 5 for rotation therewith. Preferably the rollers 2 and 3 turn oppositely, and this result can be obtained in any desirable manner for instance by the means shown. As 10 represented the shafts 4 and 5 have fixed thereto spur gears 6 and 7 in mesh with an intermediate pinion 8 fixed to a shaft 9 and adapted to be rotated in any desirable manner generally by suitable power which may be a belt or electric motor. In the construction shown the rollers 2 and 3 turn at 15 the same peripheral speeds as will be seen by an inspection of the gears already noted. Their peripheries are separated as shown 20 by Figs. 1 and 2, and the blanks are initially entered between the rollers at the converging sides of the throat thereof. The roller 2 has upon its periphery a succession of comparatively closely arranged ribs or teeth 10, while the periphery of the roller 3 has a similar set of ribs or teeth 11. Preferably the ribs or teeth 10 are diagonal or oblique to the axis of the roller 2, as shown, while the 25 ribs or teeth 11 extend in the direction of the axis of the roller 3. Cross sectionally, however, the appearance of the ribs or teeth 10 and 11 is practically the same as is shown by Fig. 5 which might represent either the roller 2 or 3. It will be apparent that the 30 outer portions of the ribs are not angular but are rounded so as to avoid any cutting of the metal of the blank. The transverse curve of the two rollers 2 and 3 I have selected for illustration is practically the same 35 and is virtually parabolic to conform to the shape of the bullet. The throat portion of the rollers as a matter of convenience is denoted by 12, while the discharge side of the rollers is denoted by 13. The straight arrow 40 in Fig. 2 indicates the direction traversed by the blank which is positively fed into the throat space between the rollers and is then conducted therefrom. The means whereby 45 this result can be obtained will be hereinafter set forth.

The framework of the machine is denoted in a general way by 14, and it has suitable bearings to support the rollers 2 and 3 and their adjuncts. In addition to this the 50 frame carries a chute 15 into which the blanks are placed and from which they are pushed by a rod 16 movable in a bearing 17 on the framework of the machine. A lever 18 operated by a cam 19 on a main operating shaft 20 serves to reciprocate the rod 16. This rod 16 is operated at the proper times 55 by means of the cam 19 to push a blank from the magazine 15 into a supporting device such as that denoted in a general way by 21. The supporting device carries the blank 60

comparatively slowly into, through and from the throat of the rollers 2 and 3, the blank during this action following a course approximately perpendicular to the plane passing through the axes of rotation of the 70 two rollers 2 and 3. The supporting device 21 as shown comprises a relatively fixed jaw 22 and a swinging jaw 23 of practically right angular shape. The head portions of the two elements 22 and 23 are thin or comparatively thin, being in any case thinner than the minimum thickness of the blank. When in operative relation as shown for instance by full lines in Fig. 6, the elements 22 and 23 are adapted to receive a blank 25 75 between their concaved seats 24. The shank of the member 22 is rigidly connected with a carrier or head such as a vertically reciprocable slide 26 while the shank of the element 23 is horizontally pivoted to the slide. To 80 the carrier 26 is pivotally connected a rod or link 27. At its lower end the rod 27 is pivotally connected with one end of a link or lever 27^a, the other end of the link or lever being pivotally connected to a bracket 27^b carried by the main frame. Carried by the lever 27^a between its ends is a stud 28 which engages a cam 29 carried by the aforesaid operating shaft 20. This mechanism 85 serves to move the slide 26 downward, a 90 spring 30 being provided for moving it upward. The spring 30 is seated in a socket in the main frame and engages at its upper end with a movable plug 31. A screw 32, threaded into a projection 33 on the slide 100 95 26, engages the top surface of the plug. In this way the spring acts to push the slide upward, thus holding the stud 28 at all times in engagement with the surface of the cam 29. By these means the slide 26, together with the supporting device 21, is regularly reciprocated vertically in timed relation with the movement of the pusher rod 16. The motions of the parts are so timed 105 that the rod 16 pushes a blank into the supporting device whenever the latter reaches its uppermost position, as shown in Fig. 6. At this time the sections 22 and 23 are in the relative position shown by full lines in Fig. 6, being yieldingly held by a spring 34 110 connecting them. The blank which is pushed by the rod 16 from the chute 15 is received into the space between the concave seats 24 on the heads of the elements 22 and 23. When this is accomplished the slide 26 115 is moved downward by the cam 29 and follows the direction of the arrow shown in Fig. 2. The blank is thus forced into the throat of the rollers 2 and 3, being carried between them and coming out in finished 120 shape. After the finished article has passed between the rollers 2 and 3, the tail of the pivoted member 23 strikes a trip or stop 35 125 on the framework 14, which causes it to swing away from the companion member 22. 130

as shown by dotted lines in Fig. 6 and thus permit the product to pass into the hopper 36 and roll down the chute 37. To facilitate the separation of the finished article from the sections or jaws 22 and 23, it may strike an ejector 38 connected to the slide 26. This action takes place immediately after the jaw portions of the parts 22 and 23 have been separated in the manner already set forth.

10 In operation, the two rollers 2 and 3 are continuously rotated in opposite directions by means of the drive shaft 9 and the gears 8, 6 and 7. The shaft 20 is thrown into action so as to cause the rod 16 to enter the lower end of the chute 15 and to push therefrom the lowermost projectile blank with the small end forward. This blank is thus moved into the space between the concave seats 24 of the members 22 and 23, then in 15 the position shown in Fig. 6. When the blank is seated between the parts 22 and 23, the entire device 21 is given a movement as already described, so as to carry the blank therewith into, through and from the throat 20 of the rollers 2 and 3. The rollers are rapidly rotated, the result being that they apply blows in rapid succession to the surface of the blank. These blows are delivered tangentially at opposite sides of the 25 blank and preferably in opposite directions. The blows are applied at gradually decreasing radii, this decrease being effected, in the embodiment shown, by moving the blank into the converging sides of the throat 30 of the rollers. The finished article is discharged into the hopper 36 from which it passes into the chute 37 to be disposed of as desired.

It will be evident that the rollers 2 and 3 are not in contact, the minimum space between them being practically equal to the minimum diameter of the finished product. When the blank enters between the two rollers, it encounters the peripheral ribs 10 and 11 which owing to the rotation of the rollers apply to the blank a rapid succession of blows. These blows result in the turning of the blank about its longitudinal axis so that all parts of its circumference 45 are brought under the action of the ribs 10 and 11 to thus not only smooth the blank and free it of all objectionable projections, but also to insure a uniform, even distribution of the metal of the blank about the 50 longitudinal center line thereof. The result is that when the diameter of the blank is reduced to the requisite extent, the longitudinal axis will exactly intersect or as near as is practically possible the center of 55 gravity of the bullet. By reason of the latter fact the bullet can definitely follow a desired path. During the reducing action the blank is properly held between the parts 22 and 23 of the supporting device which 60 positively conduct it between the two 65

rollers, the supporting device 21 does not restrict the free rotation of the blank between the rollers but it does prevent any considerable bodily movement of the blank under the influence of the blows applied by 70 the rollers.

What I claim is:

1. The herein-described method for the production of a bullet, consisting in turning a bullet blank about its longitudinal axis, in applying tangential blows in rapid succession to the blank throughout its entire length, and in supporting the blank against bodily movement under the influence of the blows. 75

2. The herein-described method for the production of a bullet, consisting in turning a bullet blank about its longitudinal axis, in applying tangential blows in rapid succession to the blank at opposite sides thereof and throughout the entire length, and in supporting the blank against bodily movement under the influence of the blows. 80

3. The herein-described method for the production of a bullet, consisting in turning a bullet blank about its longitudinal axis, in applying oppositely directed tangential blows in rapid succession to the blank at opposite sides thereof and throughout the entire length, and in supporting the blank 90 against bodily movement under the influence of the blows. 95

4. The herein-described method for the production of a bullet, consisting in turning a bullet blank about its longitudinal axis, in applying tangential blows in rapid succession to the blank throughout its entire length at gradually decreasing radii, and in supporting the blank against bodily movement under the influence of the blows. 100

5. The herein-described method for the production of a bullet, consisting in turning a bullet blank about its longitudinal axis, in applying tangential blows in rapid succession to the blank at opposite sides thereof and throughout the entire length at gradually decreasing radii, and in supporting the blank against bodily movement under the influence of the blows. 110

6. In a bullet making machine, the combination of means for applying tangential blows in rapid succession to a bullet blank, and supporting means for the blank holding it against bodily movement under the influence of the blows but permitting it to rotate about its longitudinal axis. 115

7. In a bullet making machine, the combination of means for applying tangential blows in rapid succession to a bullet blank at opposite sides thereof, and supporting means for the blank holding it against bodily movement under the influence of the blows but permitting it to rotate about its longitudinal axis. 125

8. In a bullet making machine, the com- 130

bination of means for applying tangential blows in rapid succession to a bullet blank at opposite sides thereof and in opposite directions, and supporting means for the blank holding it against bodily movement under the influence of the blows but permitting it to rotate about its longitudinal axis.

9. In a bullet making machine, the combination of means for applying tangential blows in rapid succession to a bullet blank at opposite sides thereof, and supporting means engaging the blank externally between the points of application of the blows, the supporting means holding the blank against bodily movement under the influence of the blows but permitting it to rotate about its longitudinal axis.

10. In a bullet making machine, the combination of means for applying tangential blows in rapid succession to a bullet blank at opposite sides thereof and at gradually decreasing radii, and supporting means for the blank holding it against bodily movement under the influence of the blows but permitting it to rotate about its longitudinal axis.

11. In a bullet making machine, the combination of two ribbed rollers rotatable about approximately parallel axes, and means engaging a bullet blank at opposite sides and serving to support it between the rollers in position to be engaged by both of them, the said supporting means serving to hold the blank against bodily movement under the influence of the rollers.

12. In a bullet making machine, the combination of two ribbed rollers rotatable about approximately parallel axes, the rollers being longitudinally shaped to conform to the required shape of the bullet, and means for supporting a bullet blank between the rollers in position to be engaged by both of them, the said supporting means serving to hold the blank against bodily movement under the influence of the rollers.

13. In a bullet making machine, the combination of two ribbed rollers rotatable about approximately parallel axes, ribs on one roller being inclined with respect to the axis of the roller, and means for supporting a bullet blank between the rollers in position to be engaged by both of them, the said supporting means serving to hold the blank against bodily movement under the influence of the rollers.

14. In a machine of the class described, the combination of two ribbed rollers rotatable about approximately parallel axes, means for supporting a bullet blank between the rollers in position to be engaged by both of them, the said supporting means serving to hold the blank against bodily movement under the influence of the rollers, and means for causing the two lines of engagement between the respective rollers and the blank to

approach each other as the diameter of the blank is reduced.

15. In a machine of the class described, the combination of two rollers rotatable about approximately parallel axes, means for supporting a bullet blank between the rollers in position to be engaged by both of them, the said supporting means serving to hold the blank against bodily movement under the influence of the rollers, and means for causing a relative approaching movement between the blank and the throat of the rollers, whereby the two lines of engagement between the respective rollers and the blank approach each other as the diameter of the blank is reduced.

16. In a machine of the class described, the combination of two rollers rotatable about approximately parallel axes, means for supporting a bullet blank between the rollers in position to be engaged by both of them, the said supporting means serving to hold the blank against bodily movement under the influence of the rollers, and means for moving the support to move the blank toward the throat of the rollers, thereby causing the two lines of engagement between the respective rollers and the blank to approach each other as the diameter of the blank is reduced.

17. In a machine of the class described, the combination of two rollers rotatable about approximately parallel axes, means for supporting a bullet blank between the rollers in position to be engaged by both of them, the said supporting means serving to hold the blank against bodily movement under the influence of the rollers, automatic means for successively supplying a blank to the supporting means, and automatic means for successively discharging the finished blanks from the supporting means.

18. In a machine of the class described, the combination of two rollers rotatable about approximately parallel axes, a two-part device for supporting a bullet blank between the rollers in position to be engaged by both of them, the said supporting means serving to hold the blank against bodily movement under the influence of the rollers, and means for moving one of the parts of the supporting device relatively to the other to permit the supplying and discharging of blanks.

19. In a machine of the class described, the combination of two rollers rotatable about approximately parallel axes, a two-part device for supporting a bullet blank between the rollers in position to be engaged by both of them, the said supporting means serving to hold the blank against bodily movement under the influence of the rollers, a reciprocating head for carrying the supporting device toward and from the throat of the rollers, and a trip adapted to separate

rate the parts of the supporting device at each reciprocation of the head to permit the supplying and discharging of blanks.

20. In a machine of the class described, the combination of two rollers rotatable about approximately parallel axes, a two-part device for supporting a bullet blank between the rollers in position to be engaged by both of them, the said supporting means 10 serving to hold the blank against bodily movement under the influence of the rollers, means for moving one of the parts of the supporting device relatively to the other to permit the supplying and discharging of 15 blanks, and means for automatically supplying a blank to the supporting device at each reciprocation.

21. In a machine of the class described,

the combination of two rollers rotatable about approximately parallel axes, a two-part device for supporting a bullet blank between the rollers in position to be engaged by both of them, the said supporting means serving to hold the blank against bodily movement under the influence of the rollers, 20 means for moving one of the parts of the supporting device relatively to the other to permit the supplying and discharging of blanks, and an ejector for effecting the discharge of finished blanks. 25

In testimony whereof I affix my signature in the presence of two witnesses.

FRANK O. HOAGLAND.
